UNITED STATES PATENT OFFICE.

INGLIS M. UPPERCU, OF NEW YORK, N. Y., ASSIGNOR TO THE NEOSTYLE COMPANY, OF NEW JERSEY.

MECHANICAL DRIVER.

SPECIFICATION forming part of Letters Patent No. 645,280, dated March 13, 1900.

Application filed July 31, 1899, Serial No. 725,713. (No model.)

To all whom it may concern:

Be it known that I, INGLIS M. UPPERCU, a citizen of the United States, and a resident of the city of New York, in the county and State 5 of New York, have invented certain Improvements in Mechanical Drivers, of which the following is a specification.

This invention relates to the class of devices used for transmitting rotary motion and 10 power; and it has for one object to provide a simple mechanism whereby the rotary motion of a motor may be transmitted to any machine to be driven—as a printing or sewing machine, for example.

15 Another object of the invention is to provide a simple means for transmitting from the uniformly-rotating driving-wheel a rotary motion at different rates of speed within limits as may be desired.

20 The device is particularly adapted to the use of electricity; but other motive power may be employed.

In the accompanying drawings, which illustrate an embodiment of my invention, Figure 25 1 is a plan of the invention, showing also the wheel of a machine to be driven thereby. The dotted lines show the driving mechanism out of action and the full lines show it in driving position. Fig. 2 is a plan of the carriage of my mechanical driver and the base 30 of the motor, the motor being omitted. Fig. 3 is a side elevation of my mechanical driver as seen from the side opposite the driven wheel y in Fig. 1. Fig. 4 is a view showing 35 a modification.

Referring to the drawings, X represents any suitable support, as a table or bench, and Y in Fig. 1 any machine to be driven, said machine having a driving-wheel y , provided 40 with a tire or rim y' , of rubber or other suitable material.

Secured firmly to the table X is a base-piece 45 or bed 1, and the machine Y may also be secured thereto. On the base-piece 1 is rotatively mounted at 2 a carriage or carrying-plate 3. As shown in the drawings at Fig. 1, the carriage 3 rotates or turns in a horizontal plane; but this is not material. The carriage 3 is provided with a suitable handle 4 for 50 moving it and has mounted on it an electric motor 5, inclosed in a suitable casing. The

motor has a projecting arbor 6^a, on which is secured a cone-shaped driving-wheel 6, so it may be brought into driving contact with the rim or periphery of the wheel y of the machine to be driven by turning the carriage 3 about its center of rotation 2, as indicated in Fig. 1. The arbor or shaft 6^a is longitudinally fixed and journaled at 6^b on opposite sides of the motor-casing. The motor being 60 connected up with the conductors of a circuit supplied by a suitable generator through the wires w , rotary motion will be imparted to the cone-shaped driving-wheel 6. This motion will be transmitted to the wheel y when 65 the cone-shaped driving-wheel is brought in contact with it. Where electricity is used as a motive power, it is advisable to start the cone-wheel 6 while free from the wheel y and not require any work from it until it has obtained 70 momentum. By then operating the handle 4 the driving-wheel is brought into operative contact, as shown in Fig. 1, with the wheel y and the machine set in motion.

The motor 5 may be rotatively mounted on 75 the carriage 3, the axis about which it rotates being indicated by a in Figs. 1 and 3. This axis is at right angles to the axis of rotation of the cone-shaped driving-wheel 6. As shown in Figs. 1 and 2, the axis of rotation 80 of the driving-cone is horizontal and that of the motor is perpendicular thereto or vertical. The motor 5 has a foot or base 5^a, which has in it a concentric limiting-slot 5^b, engaged by a screw or stud 3^a, which is set in the carriage 3. This foot or base 5^a, which carries 85 the motor, has also on its under side a pin 5^c, to which is secured one end of a spring 7, the other end of said spring being attached to a pin 7^a in the under side of the carriage 3. 90 Thus when the driver is turned to the position indicated by full lines in Fig. 1 and the driving-cone 6 is brought to bear near its lesser end upon the rim or periphery of the wheel y it is held up to the wheel by the elastic tension of the spring 7, and if it is desired to drive the wheel y with greater speed the carriage 3 is turned by moving the handle 4 still farther in the direction of the arrow x in Fig. 1, and this has the effect of forcing the 100 driver-cone 6 against the rim y' and at the same time moving it in the direction of the

axis across the face of the wheel y , so as to make the point of contact between the driver and wheel where the diameter of the cone is greater. Fig. 1 shows the relative positions 5 of the driver and the wheel y , whereby this result may be obtained. The foot or base 5^a has a projecting socket-piece 5^d , in which a connecting-collar is socketed. Through the center of the connecting-collar 9 a bolt 10 10 passes. The head of the bolt is on the interior of the casing of the motor 5 , and a nut $10'$ below the collar secures it to the motor-casing. The carriage 3 has on its upper face a circular projecting rim 3^b , which projects up 15 through an opening in the base 5^a and provides for the rotation of the base 5^a .

The collar 9 is held in place by a set-screw $9'$. The wires $w w$ pass up into the motor-casing through the hole in the collar along 20 side of the bolt 10 .

As the face of the cone travels across the wheel y and the circumference of the driving-wheel in contact increases the motor-base 5^a will rotate on its axis and distend the spring 25 7. The pressure of the driving-wheel is thereby increased and the speed of the driven wheel accelerated.

In order to secure the driver in position when the cone 6 is in contact with the wheel 30 or periphery of the wheel to be driven, the handle 4 has a screw-threaded shank 4^a , which screws through a socket on the carriage 3 and may be made to bear forcibly as a brake on the bed 1 and hold the driving cone-wheel up 35 in position on the rim y' . The movement of the carriage 3 about the point 2 may be limited by a slot 8 and pin, as indicated in dotted lines at 2^a in Figs. 1 and 2. It is preferred to employ an electric motor with the driver; but 40 I do not wish to confine myself to this particular motive power, as other sources of power may be used and any form of motor capable of effecting the object may be employed. Although I prefer the arrangement of parts 45 shown in Figs. 1, 2, and 3, the invention is not limited to the construction therein shown, as this may be materially varied without departing from my invention. For example, the driver would produce good results if the driving-wheel 6 , Fig. 1, were cylindrical instead 50 of conical; but no increased speed would be obtained therewith unless the wheel of the machine were made conical, as shown in the modification, Fig. 4, and the motor may be 55 approached to the machine to be driven in various ways.

In Fig. 4 a modification is shown in which the base 5^x , carrying the motor with the driving-wheel, is arranged on ways 9^x 9^x and a 60 threaded screw 10^x and wheel 11^x substituted for the handle 4 . In such modification the driving-wheel 6^x is also shown with a plain tire, and the wheel Y^x , attached to the machine, is made cone-shaped. In such arrangement the speed at which the machine is 65 driven depends upon the position of the driving-wheel on the cone.

In the drawing Fig. 4 the pivotal center on which the motor 5 moves is shown in dotted lines. The spring 7 , Fig. 3, used to hold 70 the driving-wheels of the motor in frictional contact with the driven wheel, is on the under side of the motor-casing in Fig. 4.

It will be observed that by means of my invention the motion and power are transmitted by friction. It will also be seen that the driver may readily be applied to any kind of machine it is desired to operate. It is desirable to have the face of the cone driver of suitable material to make good frictional contact, and the tire of the driving-wheel should be of rubber or other suitable material. 80

What I claim as my invention, and desire to secure by Letters Patent, is—

1. A driving mechanism, comprising a fixed 85 base, a carriage mounted movably on said base, a motor carried by said carriage and adjustably mounted thereon, a driving-wheel operated by said motor and means whereby said driving-wheel is brought in contact with 90 the driven wheel of a machine to be operated, by the movement of the motor on the carriage, substantially as shown and described.

2. A driving mechanism comprising a fixed 95 base, a carriage mounted movably on said base, a motor carried by said carriage and adjustably mounted thereon, the pivotal axis of said motor about which it is adjusted being at right angles to the plane of the carriage, a driving-wheel operated by said motor and means whereby said driving-wheel may be brought in contact with the driven wheel of a machine to be operated, substantially as shown and described.

3. A driving mechanism, comprising a fixed 105 base, a carriage mounted movably thereon, a motor carried by said carriage, a driving-wheel, having a shaft longitudinally fixed with relation to said motor and operated by said motor, said driving-wheel being adapted 110 to be brought in contact with a driven wheel one of said wheels being conical, and means by which the driving-wheel may be moved across the face of the other, whereby the speed of the driven wheel is varied, while the speed 115 of the driving-wheel remains constant, substantially as shown and described.

4. A driving mechanism, comprising a fixed base, a carriage mounted movably thereon, a motor carried by said carriage, a driving-wheel secured to a shaft longitudinally fixed with relation to said motor and operated by said motor, said driving-wheel being adapted to be brought in contact with a driven wheel, and means whereby said driving-wheel may 120 be placed in contact with a driven wheel, substantially as shown and described.

5. A driving mechanism, comprising a fixed base, a carriage mounted movably on said base, a motor pivotally mounted on the carriage, a driving-wheel operated by the motor, the axis of said driving-wheel being at right angles to the pivotal axis of the motor and means whereby said driving-wheel may be 130

brought in contact with the driven wheel of a machine to be operated substantially as described.

6. A driving mechanism, comprising a fixed base, a carriage pivotally secured to said base, a motor adjustably mounted on the carriage, a driving-wheel operated by the motor, the axis of said driving-wheel being at right angles to the pivotal axis of the carriage and means whereby said driving-wheel may be brought in contact with the driven wheel of a machine to be operated substantially as described.

7. A driving mechanism, comprising a fixed base, a carriage pivotally mounted on said base, a motor mounted pivotally on said carriage, a conical driving-wheel driven by said motor and means whereby said driving-wheel may be placed in peripheral contact with the driven wheel of a machine to be operated substantially as shown and described.

8. A driving mechanism, comprising a fixed base, a carriage pivotally mounted on said base, a motor pivotally mounted on said carriage, a conical driving-wheel operated by said motor, means whereby said driving-wheel is placed in contact with the periphery of a driven wheel of a machine to be operated and means by which the point of contact of the periphery of the driven wheel on the conical surface of the driving-wheel may be varied substantially as shown and described.

9. A driving mechanism, comprising a fixed base, a carriage mounted movably on said base, a motor mounted movably on said carriage, a conical driving-wheel operated by said motor, means whereby said driving-wheel may be placed in contact with the periphery of a driven wheel of a machine to be operated and means by which the point of contact between the surface of the conical driving-

wheel and the periphery of the driven wheel may be varied substantially as shown and described.

10. A driving mechanism, comprising a fixed base, a carriage mounted on said base, a motor carried by said carriage, a driving-wheel carried by a shaft longitudinally fixed with relation to said motor and operated by said motor and means whereby said driving-wheel may be placed in yielding contact with the driven wheel of a machine to be operated substantially as shown and described.

11. A driving mechanism, comprising a fixed base, a carriage pivotally mounted on said base, a motor mounted pivotally on said carriage, a driving-wheel, a spring adapted to hold said driving-wheel in working contact with a machine to be driven, and means whereby the carriage may be held in operative position substantially as shown and described.

12. In a driving mechanism, the combination with a base, of the carriage mounted pivotally on said base, the motor 5 pivotally mounted on said carriage, the driving-cone 6 of said motor the spring 7 connecting the motor-base with the carriage and handle 4, of the carriage, substantially as set forth.

13. In a driving mechanism, the combination with a base of the carriage adjustably mounted on said base, the motor 5 adjustably mounted on said carriage, the driving-cone 6 of said motor with means whereby the said cone may be held in contact with a machine 75 to be driven substantially as shown and described.
